UNITED STATES PATENT OFFICE.

ADDISON V. RICE, OF CHICAGO, ILLINOIS.

LUMINOUS SIGN-PLATE.

1,048,343.

Specification of Letters Patent. Patented Dec. 24, 1912.

Application filed May 14, 1910. Serial No. 561,368.

To all whom it may concern:

Be it known that I, ADDISON V. RICE, a citizen of the United States, residing at Chicago, in the county of Cook and State of Illinois, have invented certain new and useful Improvements in Luminous Sign-Plates, of which the following is a specification.

This invention relates to sign plates, and more particularly to luminous plates.

10 One object of the invention is to provide a sign plate which is both water and air tight.

A further object is to provide a simple and efficient means of fastening the plate 15 within a frame and providing means for making the frame both water and air tight.

Other objects and advantages will be apparent from the following description, and it will be understood that changes in the 20 specific structure shown and described may be made within the scope of the claim without departing from the spirit of the invention.

In the drawings: Figure 1 is a front elevation of a sign made in accordance with 25 my invention, Fig. 2 is a vertical longitudinal sectional view of the sign.

Referring to the drawings 1 represents a frame having the inwardly extending flange 30 2, the under corner of which is upwardly beveled at 2' and adapted to receive the beveled edge of the plate glass 3. A rubber gasket 4 is next placed against the glass and a mat 5 is placed on top of the rubber gasket. This forms a water proof and air tight 35 joint. Against this mat 5 is placed a plate 6 having its outer face coated with a luminous paint. On the surface of this plate are adapted to be formed letters or numbers 40 for the sign. If desired, the letters or numbers may be made with the luminous paint and the rest of the surface left darkened so that the letters or numbers will stand out from the surface.

45 The plate 6 is made in sections so that a series of letters or numbers may be interchangeably placed in the frame.

The mat 5 has an opening in its center which provides an air space between the 50 glass and the plate 6, and prevents any con-

densations of moisture which might form on the glass coming in contact with the surface of the plate 6.

As shown in Fig. 2, the back member is formed of sheet metal, and is bent as at 8 to 55 provide the bearing surface 10', which is corrugated to engage in the gasket 12. The vertical portion 12' is formed at its lower edges with the perforated ears 11', to receive the screws 9. The portion 7' of the 60 back member will be slightly bowed when the parts are screwed together, as shown.

With this sign having the luminous surface it will readily be capable of being seen in the dark and by means of the gaskets and 65 the air spaces the condensation of moisture collecting on the glass or the backs would be prevented.

From the foregoing it will readily be seen that I have provided a simple and efficient 70 sign and one which will be readily seen in the dark and has provision for preventing the destruction of the surface of the sign.

What is claimed is:

A sign comprising a frame, a beveled glass 75 seated within the frame, an inwardly directed flange to receive the beveled edge of the glass thereagainst, a rubber gasket in the frame and engaging with one face against the inner faces of the glass and the 80 flange of the frame, an open mat disposed against the opposite face of the gasket, a series of interchangeable letter sign plates disposed against the open mat to form a dead air space between the glass and the 85 said plates, a second gasket disposed against the letter sign plates, a back member having an outwardly disposed attaching flange secured to said frame, said back member being provided with an upstanding peripheral 90 corrugated rib for engagement against the second-named gasket, whereby a hollow dead air space is formed between the sign plates and said back member.

In testimony whereof I affix my signature, in presence of two witnesses.

ADDISON V. RICE.
